UNITED STATES PATENT OFFICE.

RODNEY N. MCCLURE, OF SAWTELLE, CALIFORNIA.

RECORD HOLDER.

Application filed March 27, 1922. Serial No. 547,231.

To all whom it may concern:

Be it known that I, RODNEY N. MCCLURE, a citizen of the United States, residing at Sawtelle, in the county of Los Angeles and State of California, have invented new and useful Improvements in Record Holders, of which the following is a specification.

This invention relates to a device for holding records and articles of similar character.

10 An object of the invention is to provide a record-holder in which a plurality of records may be supported horizontally in a cabinet and each record removed and replaced without disturbing adjacent records embodying a series of complementary record-supporting units so formed and constructed that the units may be disposed in stacked arrangement.

Another object is to provide a construction whereby the stacked units may be readily set in place and securely held in position in the cabinet, embodying means whereby the units will be engaged and held collectively so as to obviate separate or independent fastenings for each unit.

20 A further object is to provide a horizontally extending oscillatory record-carrier and a support therefor and to provide a means whereby the carrier may be readily moved into an advanced or retracted position.

With the foregoing objects in view, together with such other objects and advantages as may subsequently appear, my invention resides in employing the parts and the construction, arrangement and combination of parts hereinafter described and claimed and illustrated in the accompanying drawings, in which:

30 Fig. 1 is a fragmentary view in front elevation of a cabinet fitted with the record-carriers.

Fig. 2 is a plan view with parts broken away.

40 Fig. 3 is a detail in section seen on the line 3—3 of Fig. 2.

Fig. 4 is a detail of a latch for engaging the record-carrier.

50 Fig. 5 is a view in perspective illustrating the manner of assembling the units.

Fig. 6 is a perspective view of a filler plate employed to adapt the carrier for holding records of different diameter.

55 Fig. 7 is a detail in cross section as seen on the line 7—7 of Fig. 2.

Fig. 8 is a plan view illustrating a modified form of the invention.

More specifically, 9 and 10 indicate the superposed top and bottom members of a cabinet.

60 Mounted on the bottom member adjacent one side edge thereof is a series of columns 11, 12 and 13 and arranged adjacent the other edge is a complementary series of columns 14, 15 and 16. The upper ends of these columns are reduced to form shoulders 17 on which the top member 9 may seat; the reduced portions 18 extending into the top member and being internally threaded to receive screws 19. In carrying out my invention I employ a series of plate members 20 and 21 which are designed to be arranged in stacks adjacent the side portions of the cabinet in engagement with the columns; the plates 20 and 21 having openings to receive 70 the columns.

75 The plates 20 and 21 are formed with down-turned end flanges 23 and have up-turned flanges 24 on their outer edges, which flanges serve as spacers to support adjacent 80 plates in the stacks in spaced relation to each other. The plates 20 and 21 are arranged in their respective stacks with the plates in one stack in horizontal alignment with the plates in the opposite stack supported upon each pair of the horizontally aligned plates 20—21 is a movable shelf 25 constituting a record carrier. Adjacent shelves are pivoted to swing from opposite 85 sides of the cabinet; alternate shelves being 90 pivotally connected to the forward columns 11 and the intermediate shelves pivoted to the columns 14. Openings 26 are formed in extensions 27 on the shelves to receive the 95 columns 11 and 14.

95 Each shelf is formed with an arcuate flange or rib 28 to form the shelf with a recess having a wall adapted to substantially conform to the periphery of a phonograph record 29; the record being placed in position of the shelf by sliding it horizontally between the outer portions of the flange 28. The shelf 25 is designed to be oscillated to assume an advanced or retracted position and when in its retracted position, to dispose the record thereon wholly within the cabinet but when disposed in its advanced position the edge of the record will project exteriorly of the cabinet as indicated in dotted lines in Fig. 2. The forward edge 100

of the shelf 25 is spaced such distance from the flange 28 that when the record is placed on the shelf the forward portion of the record will project beyond the front edge 5 of the shelf so that it may be readily grasped and removed from the shelf and replaced thereupon. Extending vertically between the top and bottom members 9 and 10 on the forward edges thereof and adjacent to 10 the sides thereof, are panels 30—30 spaced apart to afford an opening throughout the height of the cabinet through which the records may be inserted or removed. Pivotally mounted at 31 on the outer end of each 15 shelf is a stem 32 which projects through and is guided in an opening 33 in the panel 30, which stem affords means for manually operating the shelf.

In the preferred embodiment of the invention shown in Fig. 2, the shelf is adapted to be moved to its advanced position under the action of a spring 34 which is wound around the column on which the shelf is pivoted and has one end bearing 25 against the intermediate column and has its other end bearing on the shelf in such manner as to exert an outward pressure on the latter. As a means for holding the shelf in a retracted position in opposition to the 30 spring a catch 35 is provided which embodies an arm 36 having an opening 37 whereby it may be mounted on columns 13 or 16. The outer end of the catch is formed with an inclined projection 38 adapted to 35 be engaged with a pin 39 on the shelf as shown in Fig. 4 to hold the shelf against movement under action of the spring 34. A spring 40 is arranged to act on the arm 36 in such manner as to maintain the catch 40 in its advanced position, which spring is here shown as connected at one end to the intermediate column and has its other end connected to a projection 41 on the arm 36. A slide-rod 42 bearing in the panel 30 is 45 arranged to abut against the projection 41 in such manner that on depression of the push-rod the catch may be thrown out of engagement with the shelf so that the spring 34 may move the shelf to its advanced position; the outer end of the push-rod being 50 fitted with a push button 43. In this form of the invention when the shelf is in its advanced position, limited by stop-pin 44 against which the forward edge of the shelf 55 abuts, the stem 32 will project through the plate 30 as indicated in dotted lines in Fig. 2. When it is desired to retract the shelf the stem 32 is pushed inwardly to move the pin 39 into engagement with the catch 35.

60 In the form of the invention shown in Fig. 8 the shelf is designed to be both advanced and retracted manually for which purpose the stem 32 is provided with a head 45 by means of which it may be readily grasped and pulled outwardly to advance

the shelf or pressed inwardly to retract it.

An important feature of the present invention resides in the construction whereby the assemblage of the units may be readily effected which is accomplished in the following manner; the top member 9 being removed from the columns the lower plates 20—21 are set in position by passing the columns through the openings in the plates, whereupon a shelf is set in position to seat 70 on the plates by passing a forward column through the opening 26. The spring 34 is then placed in position by passing the coils thereof over the column and engaging its ends with the intermediate column and the shelf as before described. The catch 35 is then set in position by passing the rear column through the opening therein; the spring 40 is put in place and the push-rod 85 42 disposed to engage the projection 41 on the catch. The next and the succeeding units are assembled in like manner until the desired number of units are disposed in superposed arrangement, whereupon the top member 9 is put in place and secured to the 90 columns by the screws 19. It will now be seen that the several units will be securely held in position collectively. The panels 30 are then set in position with the stems 32 projecting through the openings 33 and the 95 push-buttons 43 on the push-rods 42 extending through openings in the panels. Title-cards 46 may be fastened to the panels 30 adjacent the push-buttons 43 or stems 32 bearing the title of the record carried by the shelf controlled by the push-rods or stems.

As a means for adapting the shelf to receive records of various diameters filler-blocks 47 (shown in Fig. 6) are employed, 105 which filler-blocks have an arcuate rear edge 48 adapted to conform to the arcuate flange 28 of the shelf and having an arcuate forward edge 49 adapted to conform to the periphery of a record having a radius less than that of the flange 28.

I claim:

1. In a record-holder, a column, a series of independently separable superimposed plates 115 slidably engaged on said column with adjacent plates spaced apart, and an oscillatory record-carrying shelf interposed between adjacent plates and pivotally connected to the column.
2. In a record-holder, a plurality of separable plates arranged in a stack with superposed plates bearing upon each other; means for spacing adjacent plates apart, a column passing through the stack of plates to hold the plates collectively against movement relative to each other, and a shelf interposed between adjacent plates having an extension formed with an opening through which the column is passed whereby said column will serve as a pivotal mounting for said shelf.

3. In a record-holder, a plurality of plates arranged in a stack and spaced apart, a series of columns passing through said plates serving to hold the plates collectively against movement relative to each other, a second stack of a plurality of plates, columns extending through said last named plates, the plates in one column being in alignment with the plates of the other column, and a series of shelves slidably supported upon the plates in the stacks, said shelves being pivotally mounted to swing horizontally on said plates.

4. In a record-holder, a plurality of plates arranged in a stack and spaced apart, a series of columns passing through said plates serving to hold the plates collectively against movement relative to each other, a second stack of a plurality of plates, columns extending through said last named plates, the plates in one column being in alignment with the plates of the other column, and a series of shelves slidably supported upon the plates in the stacks, alternate shelves being pivotally mounted on a column in one of the stacks of plates and the intermediate shelves being pivoted on the column in the other stack of plates.

5. In a record-holder, a plurality of superimposed plates, each of which is formed with down-turned flanges whereby the adjacent

plates will be supported in spaced relation to each other, each of said plates being formed with openings aligning with the openings in the adjacent plate; means passing through the opening in the superposed plates for holding the plates collectively against movement relative to each other, and horizontally movable record-holding shelves interposed between and slidably supported on said plates.

6. In a record-holder, a plurality of superimposed plates, each of which is formed with down-turned flanges whereby the adjacent plates will be supported in spaced relation to each other, each of said plates being formed with openings aligning with the openings in the adjacent plate; means passing through the openings in the superposed plates for holding the plates collectively against movement relative to each other, and horizontally movable record-holding shelves interposed between and slidably supported on said plates, a complementary stack of superposed plates co-operating with the first named plates in supporting said shelves; means for pivotally mounting said shelves; spring means for advancing the shelves; and means for holding the shelves in a retracted position in opposition to said spring means.

RODNEY N. McCLURE.
